TOY FIGURE

Reuben B. Klamer, 245 S. Barrington Ave.,
Los Angeles, Calif. 90049

Filed Aug. 2, 1967, Ser. No. 8,093

Term of patent 14 years

(Cl. D34—2)

FIG. 1

The essential features of my design are shown in full lines on the drawing.

I claim:

The ornamental design for a toy figure, substantially as shown and described.
